UNITED STATES PATENT OFFICE.

THOMAS W. CAPEN, OF CHICAGO, ILLINOIS, ASSIGNOR TO THE GATES IRON WORKS, OF ILLINOIS.

JOURNAL-BOX FOR STAMP-MILLS.

SPECIFICATION forming part of Letters Patent No. 628,447, dated July 11, 1899.

Application filed April 7, 1899. Serial No. 712,091. (No model.)

To all whom it may concern:

Be it known that I, THOMAS W. CAPEN, a citizen of the United States, residing at Chicago, in the county of Cook and State of Illinois, have invented certain new and useful Improvements in Journal-Boxes for Stamp-Mills, of which the following is a specification.

My invention relates particularly to that class of stamp-mills in which there are two or more posts adapted to sustain a cam-shaft in position, which cam-shaft is supplied with a number of cams adapted to raise stamps which are allowed to drop successively and pulverize material between a head on their lower portions and a mortar-bed.

The invention has more particular relation to the construction of the box in which a cam-shaft has its bearings, all of which will more fully hereinafter appear.

20 The principal object of my invention is to provide a stamp-mill with a simple, economical, and efficient box for supporting the cam-shaft; and the invention consists in the features, combinations, and details of construction hereinafter described and claimed.

In the accompanying drawings, Figure 1 is a perspective view of a cam-shaft box constructed in accordance with my improvements; and Fig. 2, a vertical sectional elevation taken on line 2 of Fig. 1, looking in the direction of the arrow and showing the box as it appears when attached in position.

In the art to which this invention relates it is well known that the weight of the cam-shaft of a stamp-mill rests entirely on the lower portion of the cam-shaft box, for the reason that the work performed by the cam-shaft is to lift the stamp-rods only. As there are a large number of successive shocks applied to the machine, in that the act of raising the stamp-rods is intermittent, the cam-shaft is necessarily subjected to a large number of violent blows. Consequently it is important that the cam-shaft box be sustained immovably in position. In order to accomplish this result, it is desirable that the standards or posts which sustain the boxes should be cut away to form a seat to receive the box. As a consequence of this cutting away it is difficult to get at the box-cap, which is nothing more or less than a dust-guard, for the pur-

pose of removing or inserting it. Hence the use of bolt-and-nut mechanism is undesirable.

My invention therefore is intended, primarily, to provide a simple, economical, and efficient box for a stamp-mill with a removable cap and means for holding it rigidly in position and at the same time permitting it to be removed whenever desirable or necessary, as will hereinafter more fully be shown.

In illustrating and describing my invention I have only illustrated and described so much of the mechanism as is old, taken in connection with what I consider to be new, as will properly disclose the invention and enable those skilled in the art to practice the same, leaving out of consideration other and well-known mechanisms, which if illustrated and described here would only tend to prolixity, confusion, and ambiguity.

70 In constructing my improvement I use the usual standard or post A, which forms a portion of the supporting-frame of a stamp-mill, and cut it away, so as to form the seat a. Resting upon the seat in this post is the box proper, comprising a lower portion B, which is babbitted at b to form the bearing for the cam-shaft journal. This box, as will appear from an inspection of the drawings, has a base portion b' made in the shape of 80 an angle-plate, upon which the bearing is secured by a very light web-frame b². The box is also provided with an upwardly-extending portion or flange B', provided with bolt-holes b³, through which securing-bolts C are passed. 85 Securing-bolts C' are also passed through bolt-holes b⁴ in the angle-plate, as shown in the drawings.

In order to hold a dust-cap D in engagement with the box proper, the cap is provided 90 with two lugs d and d' at or near its inner lateral edge and arranged to provide a space d² between the same. The upwardly-extending flange of the box is provided with a lug b⁵, arranged, when the cap is in position, to 95 be directly over the space between the lugs on such cap. The cap is also provided with a projecting lug d³ on its opposite lateral edge, which in turn has a pin d⁴ extending down into an opening in the box. (See Fig. 2.) A 100 wedge E is provided and driven between the two lugs on the inner lateral edge of the cap

and the lug on the upwardly-extending flange of the box, which rigidly secures the cap in position, while the pin or stud d^4 prevents its displacement longitudinally. The cap is provided with the usual oil-cup d^5 , and the lower part of the box is provided with a trough G , in which the waste oil is caught and from which it may be drawn off by means of the waste-pipe g .

10 In operation the cap is placed in position with its stud in the hole of the box and the wedge driven into place, which rigidly holds the cap in position. When for any reason it is desirable to remove the cap, the wedge is 15 driven out and the cap raised, so that the outwardly-extending lug on the upwardly-extending flange passes through the space d^2 , when its cap may be pulled out laterally.

From the foregoing description of construction and operation it will be seen that the use 20 of bolts and nuts, so far as the dust-cap is concerned, is dispensed with and that the dust-cap can be inserted in position or removed therefrom without the use of wrenches or similar tools, which would be very awkward to handle in the recess of the standard.

I claim--

1. In mechanisms of the class described, a box provided with an upwardly-extending flange and a semicylindrical bearing, a dust-cap provided with at least two lugs on its inner lateral edge, a lug on the upwardly-extending flange of the lower portion of the box arranged above and between the lugs on the cap, and a wedge arranged to be driven between the lugs on the cap and on the box portion proper to hold the parts together, substantially as described.

2. In mechanisms of the class described, a cam-shaft box provided with a lower portion having a right-angular base an upwardly-extending flange and a semicylindrical bearing,

a cap portion provided with two lugs on its inner lateral edge adjacent to the upwardly-extending flange of the box, a lug on the upwardly-extending flange of the box arranged above and between the lugs on the cap, and a wedge adapted to be passed between the lugs on the cap and box to hold the parts in position, substantially as described.

3. In mechanisms of the class described, a cam-shaft box provided with a lower base portion having a semicylindrical bearing thereon and an upwardly-extending flange, a semicylindrical cap portion provided with two lugs on its inner lateral edge and a projecting stud on its outer lateral edge adapted to enter a recess or opening in the lower portion of the box, a lug on the upwardly-extending flange of the box proper arranged above and between the lugs on the inner edge of the cap, and a wedge adapted to be passed between the lugs on the box and on the cap to secure the parts together, substantially as described.

4. In mechanisms of the class described, a cam-shaft box comprising a lower right-angular base provided with an oil-trough a semicylindrical bearing portion supported thereon and an upwardly-extending flange portion, a semicylindrical cap portion provided with two lugs on its inner lateral edge, a lug and stud on its outer lateral edge adapted to enter a recess or opening in the outer lateral edge of the box proper, a lug on the upwardly-extending flange of the box proper arranged above and between the lugs on the cap, and a wedge arranged to be driven between the lugs on the box and cap to secure them together, substantially as described.

THOMAS W. CAPEN.
